Inventor
Sam'l Lloyd

UNITED STATES PATENT OFFICE.

SAMUEL LLOYD, OF WASHINGTON CITY, DISTRICT OF COLUMBIA.

IMPROVEMENT IN HEATING AND VENTILATING RAILROAD-CARS.

Specification forming part of Letters Patent No. 74,386, dated February 11, 1868.

To all whom it may concern:

Be it known that I, SAMUEL LLOYD, of the city of Washington, District of Columbia, have invented a new and useful Method of Heating and Ventilating Railroad-Cars; and the following is a full, clear, and exact description thereof, reference being had to the accompanying drawing, and to the letters of reference marked thereon.

Figure 1 is a vertical section through a locomotive and heating-car. Fig. 2 is a sectional view of the coupling-pipe for conveying heat from car to car.

The object of my invention is to heat and ventilate a train of railroad-cars by means of hot and cold air conveyed into the cars from apparatus on locomotive, and in a heating and ventilating car, so as to obviate the use of stoves in each car, thereby giving greater security to life and economy of room and fuel.

To enable others skilled in the art to make and use my invention, I will describe it more fully, reference being had to the accompanying drawing, and to the letters marked thereon.

Letter A, Fig. 1, is a locomotive, having a hood or opening, *a*, underneath the cow-catcher, for the purpose of gathering the air, which is conveyed by the pipe *b* through the flue-chamber, and spirally around the interior of the smoke-stack of the locomotive, thereby heating the air in the pipe. The pipe *b*, leaving the smoke-stack at its base, and passing along the outside of the boiler, beneath the locomotive, is connected with the horizontal pipe *c*, which connects by the flexible coupling *D* with another horizontal pipe, *d*, which is coupled with and conveys air to the passenger-cars, the hood *a* supplying a current of pure air, which it is unnecessary to pass through water, and may be either hot or cold, the change being effected by means of the valve *x*.

Letter B, Fig. 1, is a fire-proof car, made of or cased in wrought-iron or other suitable material, placed in front of the passenger-cars, and containing heating and forcing apparatus, which I will now describe.

Letter E is the space for a caloric-engine which I use for driving the blower *H* and the agitator *p*, and exhausting into the receiver

G by means of the pipe *o*, after first passing the exhaust hot air through a deodorizing process.

Letters *e e* is a jacket inclosing, as far as practicable, the hot-air chamber of the caloric-engine. The cold air is received into the jacket by means of a hood, *r*, and pipe *y*, the supply being regulated by the valve *u*. It is then passed around the hot-air chamber of the caloric-engine by means of a spiral flue, the sections of which are marked *ffff*, and by the pipe *j j* and valve *m*, forced by the blower *H* through the pipe *o* into the receiver *G*, or by means of the valve *l* and pipe *n*, connecting with the pipe *o*, passed directly into the receiver by means of the draft created by the movement of the train.

Letter *F* is a furnace for heating air—as many as necessary being used—jacketed, and regulated by valves, as described in the caloric-engine, and containing a spiral coil of pipe, *g g*, in the fire-chamber, through which a portion of the air passes, thereby giving a greater heating-surface, the heated air from the furnace being conveyed by the pipe *h* into the pipe *j* at *k*. The connection with the furnace may be closed or regulated by means of the valve *i*.

Letter *s* is a hood for supplying the cars with cool air, and is connected with the blower *H* by means of the pipe *p*, and closed by the valve *v* when hot air is used; but the air can be taken directly into the receiver by means of a connection between the pipes *t* and *o* and the draft occasioned by the movement of the train.

Letter *G* is a receiver, partly filled with water, through which the air passes by means of the pipe *o*, whose mouth opens under the water.

Letter *p* is an agitator run by means of the caloric-engine, or a pulley attached to the axle of the car, and working in the water directly over the mouth of the pipe *o*, thereby driving the air through the water, so that it will be thoroughly filtered and freed of dust.

Letter *q* is a supply-pipe, having its mouth opening in the top of the receiver, and is connected with the conducting-pipe *d*, conveying the purified air from the receiver into the pas-

senger-cars. The heating and ventilating car can be run either end first by reversing the hoods *r r* and *s*, and can be used independent of the heating and ventilating apparatus on the locomotive by closing either of the valves *w w* which may be in front of the supply-pipe *q* as the car runs.

The air, either hot or cold, is distributed through the cars by means of a pipe or pipes, cased or not with a non-conductor of heat, running along the bottom of the cars, and having one or more registers opening in each car. The open end of the fixed conducting-pipe of the last car can be closed with a screw-cap, so that all the air will pass into the cars, each car being provided with one or more ventilating-hoods on top of each car, with valve-openings, so as to regulate the temperature and ventilation.

Letters *d d*, Fig. 2, are portions of the fixed conducting-pipes, and are made of any suitable material, incased or not in a non-conductor of heat. *b' b'* are male screws or couplings. *c'* is a female screw-coupling attached to and working freely around only one end, *a'*, of the hose or flexible connection *D*, so that the other end, *e'*, may have a free lateral motion in a stuffing-box, *f'*, so as to facilitate the coupling or uncoupling of the cars, and allow for the free lateral motion of the cars. Both ends of the fixed conducting-pipes *d d* are provided with male screws *b' b'* and stuffing-boxes *f' f'*, with a packing of rubber, *g' g'*, or other suitable material, making an air-tight connection, so that the flexible connection can be coupled to either end of the fixed conducting-pipes *d d*, so that it will not be necessary to reverse the ends of the cars to make connection.

Letter *a'* is an extension of the connection

into the stuffing-box, upon which the connection is coupled, taking the strain off of the screw-coupling, and supporting the flexible connection-pipe *D* when the cars are uncoupled, so that the loose end *e'* will not drag on the ground.

Letter *h'* is a flat steel spiral, firmly connected with the ends *a'* and *e'*, keeping the hose extended and in a proper shape, covered with a layer of Holland duck, a layer of vulcanized rubber, the whole protected by a covering of stout leather, forming a flexible hose or connection, which takes the strain caused by the vibratory motion of the cars off from the fixed conducting-pipes *d d*, and allows for the free turning of curves.

Having thus fully described my invention, what I claim as new, and desire to secure by Letters Patent, is—

1. The valve *x*, in combination with the heating-pipe *b* and the ventilating-pipe *c*, in the manner set forth.
2. Heating and ventilating a train of cars by means of a fire-proof heating-car containing furnaces, caloric-engine, blower-agitator, receiver, and pipes, arranged and operating substantially as and for the purpose herein set forth.
3. A flexible connecting-pipe forming a continued hot-air flue between cars, and attached to the heating or ventilating pipes by means of a screw-cap at one end and a sliding tube at the other, in manner and for purpose set forth.

SAML. LLOYD.
